Inventor,

August Wilhelm

United States Patent Office.

AUGUST WILHELM, OF PHILADELPHIA, PENNSYLVANIA.

Design No. 4,693, dated February 28, 1871.

DESIGN FOR A REFLECTOR.

The Schedule referred to in these Letters Patent and making part of the same.

To all whom it may concern:

Be it known that I, AUGUST WILHELM, of the city of Philadelphia, in the county of Philadelphia and State of Pennsylvania, have invented and designed a new and original shape for a Light-Reflector for Lamps, Street-Lanterns, &c., of which the following is a clear and exact description, reference being had to the accompanying drawing making a part of this description, and to the letters of reference marked thereon.

The drawing represents a vertical longitudinal section through the center of the said reflector.

The inside or reflecting-surface of the reflector is concavo-convex.

$c b a c b a$ is the concave part of the reflector, and is formed of the convex curves $c b c b$, and of the concave curves $b a b a$.

$a b' c' b' a$ is the convex part of the reflector, and is formed of the concave curves $a b' a b'$, and of the convex curves $b' c' b' c'$.

The concave curves $b a a b' b a a b'$ are elliptic,

The convex curves $c b c' b', c b c' b'$ are segments of circles.

A reflector shaped as herein shown and described can be circular or polygonal.

A number of lights can be placed on the focus line ff .

The dotted lines are merely illustrative of the manner of designing the reflecting-surface of the reflector $c b a b' c' b' a b c$, and of the resultant direction of the reflected rays of light coming from the focus line ff , and therefore form no part of the design; but

Having shown and described the particular shape of the reflector, $c b a b' c' b' a b c$,

What I claim as my invention, and desire to secure by Letters Patent, is—

The design for a reflector herein shown and described.

AUGUST WILHELM.
